(57) **CLAIM**

The ornamental design for a videoconferencing camera, as shown and described.

DESCRIPTION

FIG. 1 is a front perspective view of a videoconferencing camera, showing our new design in a first configuration; FIG. 2 is a front elevational view thereof;

FIG. 3 is a rear elevational view thereof;

FIG. 4 is a top plan view thereof;

FIG. 5 is a bottom plan view thereof;

FIG. 6 is a right side elevational view thereof;

FIG. 7 is a left side elevational view thereof;

FIG. 8 is a front perspective view thereof, shown in condition of use and mounted on a bracket disclosed in broken lines to illustrate an environment;

FIG. 9 is a left side elevational view thereof, shown in condition of use with a bracket and a cable disclosed in broken lines to illustrate an environment;

FIG. 10 is a front perspective view thereof, shown with the base pivoted in a second configuration;

FIG. 11 is a front elevational view thereof;

FIG. 12 is a rear elevational view thereof;

FIG. 13 is a top plan view thereof;

FIG. 14 is a bottom plan view thereof;

FIG. 15 is a right side elevational view thereof;

FIG. 16 is a left side elevational view thereof;

FIG. 17 is a front perspective view thereof, shown in condition of use and mounted with a bracket disclosed in broken lines to illustrate an environment; and,

FIG. 18 is a left side elevational view thereof, shown in condition of use with a bracket and a cable disclosed in broken lines to illustrate an environment.

The broken lines depict portions of the videoconferencing camera in which the design is embodied that form no part of the claimed design. Additionally, the broken lines showing a bracket and cable in FIGS. 8–9 and 17–18 represent environmental structure and form no part of the claimed design.

1 Claim, 15 Drawing Sheets
